I. D. BLOCK ET AL

COMB

Filed Dec. 10, 1927

FIG. 1.

FIG. 2.

FIG. 3.

Inventor

I. D. Block
G. B. Canada
By *Alfred C. Knobell* Attorney

UNITED STATES PATENT OFFICE.

ISAAC D. BLOCK AND GEORGE B. CANADA, OF MEMPHIS, TENNESSEE.

COMB.

Application filed December 10, 1927. Serial No. 239,212.

This invention relates to new and useful improvements in combs, and particularly to combs used by barbers.

With the ordinary straight flat comb, now in general use, there is great inconvenience, on the part of both the sitter and the barber, while working around the ears of the sitter. The barber finds it difficult to manipulate the comb, without bending the sitter's ear down out of the way. This is annoying to the sitter. Also, it is difficult to rock the comb, so as to elevate the portion of the hair engaged in the teeth of the comb, to permit use of the scissors thereon. It is therefore the principle object of the present invention to provide a comb of such construction that the barber may easily and quickly work around the ears of the sitter, to cut the hair, and without inconvenience, or annoyance to the sitter.

Another object is to provide a comb of this character with which the barber may easily operate in the hollow portions of the neck of the sitter.

Other objects and advantages will be apparent from the following description when taken in connection with the accompanying drawing.

In the drawing:

Figure 1 is a perspective view of one form of the comb wherein the same is bent into offset relation at a point intermediate the set of coarse teeth and the set of fine teeth.

Figure 2 is a perspective view of another form of the comb wherein the offset is made wholly within the set of fine teeth.

Figure 3 is another perspective view of the comb showing the offset made in the intermediate portion of the comb, and with the adjacent coarse and fine teeth cut off on diverging lines, whereby to provide a substantially V-shaped opening in the center of the toothed edge of the comb.

Referring to the accompanying drawing, and particularly to Figure 1, there is shown a comb including a back 10 having the series of coarse teeth 11 and the series of fine teeth 12. The general outline of the comb is tapering, with the smaller end containing the fine teeth. The back of the comb is bent intermediate its length, and intermediate the sets of different sized teeth, so that the end having the coarse teeth is offset into parallel relation, but in a different plane, to that of the end having the fine teeth. The barber grasps the proper end of the comb, and ap-

plies the other end to the head of the sitter, and it will readily be seen that the portion grasped in the operator's hand will lie in spaced relation to the sitter's head or neck, with the result that manipulation of the comb, so as to extend the teeth away from the sitter, so as to lift the hair for the application of the scissors, is made easy. Furthermore, when the comb is manipulated around the ear of the sitter, the operator's hand will be spaced from the sitter's head, and also from the ear, thus obviating the usual annoying practice of bending the ear down, to operate on the hair inwardly of the ear. This form of comb is also very useful when cutting the hair in the hollow portions of the neck of the sitter, the operator placing the forward end of the comb in such hollow, and grasping the other end of the comb in the hand, whereby the hand will be elevated from the sitter's neck.

Sometimes the operator desires a comb wherein the offset, or bend, is placed nearer the forward end of the comb, and in this event, a comb, as is shown in Fig. 2, is provided. It will be noted that the bend is made at 13, which is intermediate the length of the series of fine teeth, but this bend may be made intermediate the coarse teeth, if desired.

In the form shown in Figure 3, the comb is bent intermediate its length, with the end portions offset to lie in different planes, parallel to each other. The toothed edge of the comb is cut in a V-shape, as shown at 14, one oblique line of such cut extending across the innermost of the finer teeth, while the other oblique line of the cut extends across the innermost of the coarser teeth. In this form, not only does the offset or bend facilitate the manipulation of the comb around the ears of the sitter, and in the hollows of the neck, but the V-shaped cut also serves to further prevent contact of the teeth of the comb with the ear.

What is claimed is:

1. A toilet comb including a back and a series of teeth, said back including end portions each of which carries a longitudinal series of teeth, said end portions being offset with relation to each other, and a transverse back portion connecting the inner ends of the end portions and having teeth.

2. A toilet comb including a back and a continuous series of teeth, the intermediate portion of the comb being formed with a

transverse bend, the intermediate portion of the series of teeth being formed with a V-shaped cut whereby the teeth in the cut are graduated in length from the bend toward

5 the outer ends of the cut.

3. A toilet comb including a back having a series of teeth, the intermediate portion of the back being formed with a transverse bend whereby to offset the end portions of

the comb into parallel planes, the teeth adjacent the said bend being cut off on oblique lines converging inwardly toward said transverse bend.

In testimony whereof, we affix our signatures.

ISAAC D. BLOCK.
GEORGE B. CANADA.
